United States Patent

Des. 238,355

Patented Jan. 6, 1976

238,355

BUILDING

Jerry D. Pierson, % M. J. Harwood Co., Inc.,
2502 Broadway, San Antonio, Tex. 78215

Filed Dec. 27, 1973, Ser. No. 428,789

Term of patent 14 years

Int. Cl. D25—03

U.S. Cl. D13—1 E

FIG. 1

FIG. 2

FIG. 3

FIG. 1 is a rear perspective view of a building showing my new design;

FIG. 2 is a top plan view; and

FIG. 3 is a front elevation view thereof, the rear and sides being a mirror image thereof except that the rear and sides of the pedestal are plain and unornamented.

I claim:

The ornamental design for a building, as shown and described.
